UNITED STATES PATENT OFFICE.

CHARLES A. WAITZ, OF ROUSEVILLE, PENNSYLVANIA.

PUMP.

Application filed February 16, 1920. Serial No. 359,112.

To all whom it may concern:

Be it known that I, CHARLES A. WAITZ, a citizen of the United States, residing at Rouseville, in the county of Venango and 5 State of Pennsylvania, have invented new and useful Improvements in Pumps, of which the following is a specification.

The invention relates more particularly to pumps adapted to oil wells and is particularly advantageous in connection with oil wells in which the working barrels have become deficient. In this connection the trapping of the sand is particularly desirable and this invention accomplishes this purpose 10 in a simple manner. The other features of the invention will appear from the specification and claims.

The invention is illustrated in the accompanying drawings as follows:—

20 Fig. 1 shows a vertical central section through a pump.

Fig. 2 a bottom view of the clutch element on the same.

25 Fig. 3 a side elevation of the top of the working barrel.

1 marks the strainer, 2 the standing valve fitting at the top of the strainer, 3 the original working barrel tube, 4 the original standing valve, 3^a a coupling at the upper 30 end of the orginal working barrel, and 3^b the well tubing. These are of usual construction.

The inserted working barrel 5 has a standing valve fitting 6 at its lower end in which 35 a standing valve 7 is arranged. An intake tube 8 is secured to the fitting 6 and extends downwardly preferably to within the original working barrel tube. It is anchored in the original working barrel tube and has a 40 closure formed by cups 9 which are preferably arranged intermediate the ends of the original working barrel tube. A closure cap 10 rests on the upper end of the working barrel. It has a bevelled bottom 11 and is 45 of a size approximating the size of the tubing 3^b. A coupling 12 is arranged in the intake tube 8 and this coupling rests on the cap 10. The distance between the closure 9 and the coupling 12 is such as to give some 50 freedom of movement so that the cap 10 may be jarred loose if necessary.

A sand trap pipe 13 is secured to the cap 12 and extends upwardly surrounding the inlet tube 8. It will be understood that the 55 inlet tube may be made of any length desired so as to give the sand trap the greatest ca-

pacity possible. In some wells the height of the inserted barrel may be well above the original barrel tube. In other wells it may be necessary to lower the inserted barrel to 60 nearer the elevation of the original barrel tube and this limits to some extent the length of the sand trap.

A working plunger 14 is arranged in the inserted barrel and a sucker rod 15 extends 65 upwardly from the plunger. The sucker rod passes through a cap 16 at the upper end of the barrel, this cap having lateral openings 16^a so that the pumped liquid may pass out into the tubing. Corrugations 17 are arranged on the upper part of the cap, these forming clutch elements which are adapted to engage corrugations 18 on the underside of a coupling 19 on the sucker rod. The coupling is so distanced from the plunger that 70 the clutch elements may be brought into engagement before the plunger reaches the standing valve. The purpose of this is to permit of putting a certain amount of strain 75 on the joints of the sucker rods so that they 80 may be tightened or loosened.

It will be noted that the cap 16 prevents the settling of the sand into the working barrel after the cessation of the pumping action. The sand as it settles back into the column of oil in the tubing, therefore, settles 85 into the sand trap 13. The cap 10 prevents the settling of the sand on the anchor or closure 9. Consequently if it is necessary to pull the pump there is not a great deal of 90 difficulty in loosening the packing 9. If there is sand outside the sand trap the jar-ring against the cap 10 by the packing 9 will loosen this.

The bottom of the cap 10 being bevelled 95 provides a means by which any scale or irregularities in the tubing may be removed; that is to say, the cap 10 may be driven through such reduced portions, thus clearing 100 the way for the sand trap and for the other parts of the device.

What I claim as new is:—

1. In a pump, the combination of a tubing; a working barrel within the tubing; a plunger within the barrel; a cap on the barrel with lateral openings discharging into the tubing, said cap having clutch elements on its upper surface; a rod secured to the plunger and extending through the cap, said rod having an enlargement with a clutch element adapted to operate on the clutch element on the cap. 105 110

2. In a pump, the combination of a tubing; a working barrel within the tubing; an intake tube extending downwardly from the working barrel within the tubing, the intake being anchored and provided with a closure relatively to the tubing; a plunger within the barrel; and a sucker rod secured to the plunger.
3. In a pump, the combination of a tubing; a working barrel within the tubing; an intake tube extending downwardly from the working barrel within the tubing, the intake being anchored and provided with a closure relatively to the tubing; a plunger within the barrel; and a sucker rod secured to the plunger, the space surrounding the intake tube forming a sand trap.
4. In a pump, the combination of a tubing; a working barrel within the tubing; an intake tube extending downwardly from the working barrel within the tubing, the intake being anchored and provided with a closure relatively to the tubing, the space surrounding the intake tube forming a sand trap; a cap arranged on the upper end of the working barrel; a plunger in the working barrel; and a sucker rod extending through the cap.
5. In a pump, the combination of a tubing; a working barrel tube secured to the tubing; an insert working barrel arranged above the working barrel tube; an intake tube extending from the insert working barrel downwardly to within the working barrel tube; and a closure on the intake arranged in the working barrel tube.
6. In a pump, the combination of a tubing; a working barrel tube secured to the tubing; an insert working barrel arranged above the working barrel tube; an intake tube extending from the insert working barrel downwardly to within the working barrel tube; a closure on the intake arranged in the working barrel tube; and means on the intake tube resting on the top of the working barrel tube.
7. In a pump, the combination of a tubing; a working barrel tube secured to the tubing; an insert working barrel; an intake tube extending from the insert working barrel downwardly to within the working barrel tube; a cap on the working barrel tube through which the intake tube extends; and a shoulder on the intake tube resting on the cap, said shoulder being distanced from a closure to provide a jar for the cap.
8. In a pump, the combination of a tubing; a working barrel within the tubing; a plunger within the working barrel; an intake tube extending downwardly from the working barrel; a closure and anchor in the tubing from which the intake extends; and a sand trap below the working barrel and above the closure and surrounding the intake tube.
9. In a pump, the combination of a tubing; working barrel tube secured to the tubing; an insert working barrel; an intake tube extending from the insert working barrel downwardly to within the working barrel tube; a cap resting on the working barrel tube through which the intake tube extends; and a sand trap carried by the cap and surrounding said intake tube.
10. In a pump, the combination of a tubing; working barrel tube secured to the tubing; an insert working barrel; an intake tube extending from the insert working barrel downwardly to within the working barrel tube; a cap resting on the working barrel tube through which the intake tube extends; a sand trap carried by the cap and surrounding said intake tube; a closure on the intake tube within the working barrel tube; and means on the intake tube resting on the cap, the distance between the closure and the means being sufficient to permit of a jarring of the cap.

In testimony whereof I have hereunto set my hand.

CHARLES A. WAITZ.
